UNITED STATES PATENT OFFICE

2,616,821

LAMINATED BOX TOE STIFFENING MATERIAL

Raymond B. Harrison, Braintree, Mass., assignor to Beckwith Manufacturing Company, Dover, N. H., a corporation of New Hampshire

Application June 20, 1947, Serial No. 756,002

1 Claim. (Cl. 154—46)

1

This invention comprises a new and improved laminated box toe material and a novel process of manufacturing the same.

In the manufacture of boots and shoes it is essential that the box toe blanks which are relied upon for stiffening the toe portion of the shoe should carry a sufficient load of either thermoplastic or solvent-softening stiffening material to supply the requisite stiffness and resiliency in the finished shoe and should also be permanently united to the lining of the shoe or to the outer integument of the upper in case no lining is used. If a permanent union is not made the material of the box toe is likely to let go from the rest of the upper and sag and drop inside the shoe and thus cause great discomfort to the user. The principal object of the present invention is to provide an improved box toe material to which an adequate supply of stiffening compound may be rapidly applied and which in its finished condition will present a napped surface well adapted to receive and contain a copious coating of cement prior to being incorporated in the structure of the upper.

In one aspect therefore the invention comprises a process of making laminated box toe material by bringing together and uniting by pressure a dry napped sheet of fabric and a sheet of fabric saturated with thermoplastic or solvent softening material in liquid form, and therefore providing a composite sheet having an internal film of stiffening material and lofted nap on one of its exterior surfaces. The improved construction thus derived may be contrasted with box toe material heretofore available and produced by passing napped fabric sheets through a liquid impregnant with the result that the nap is flattened so that it will not readily hold enough cement to insure permanent anchorage in the upper of the shoe.

Going more into detail it is proposed to develop a composite laminated sheet from two plies of textile material each of which may be either single or double napped. One of these sheets is passed through a bath of liquid impregnant and then affixed by pressure to the other which is brought to the line of union in a dry condition so that its outer napped surface remains lofted and unflattened in the finished product. The nap of the saturated sheet meanwhile forms a bibulous carrier for the liquid impregnant and if the dry sheet is double napped the nap upon its inner face being united with the nap of the saturated sheet increases the carrying capacity of the composite sheet so that a film of sub-

2

stantial thickness is deposited between the two sheets.

These and other characteristics and features of the invention will be best understood and appreciated from the following description of a preferred manner of carrying it out as illustrated in the accompanying drawings,

Fig. 1 is a diagrammatic view illustrating the process,

10 Fig. 2 is a view in perspective of a portion of the composite sheet product,

Fig. 3 is a plan view of a box toe blank made therefrom, and

15 Fig. 4 is a view of the material in cross-section on a greatly enlarged scale.

In Fig. 1 is conventionally represented a tank 10 containing a stiffening composition 11 in liquid form and provided with guide rollers 12, 13 and 14. A fibrous textile sheet 15 having a single 20 napped surface uppermost is led from a coil 16 over the guide roll 12 and immersed in the impregnant 11 by being carried around the roll 13. The sheet then passes upwardly over roll 14 with which cooperates a squeeze roll 17. At 25 this point surplus liquid impregnant is stripped from the sheet and returned to the tank. The saturated sheet is now guided in a horizontal path between a pair of squeeze rolls 18 and 19.

A second single napped sheet 20 having its 30 napped surface uppermost is led from a coil 21 directly to the squeeze rolls 18 and 19 in dry condition. In passing through the bite of the rolls 18 and 19 the two sheets are adhesively and 35 permanently united into a composite laminated sheet having lofted nap 22 upon its upper surface. Enclosed between the two plies of the composite sheet is a continuous film 23 of stiffening compound as best shown in Fig. 4. It will be understood that the nap of the sheet 15 serves as

40 a bibulous carrier for the liquid stiffening composition and that the sheet 15 may be single or double napped as preferred. The liquid impregnant completely saturates the sheet 15 and when that sheet is combined with the dry sheet 20 the impregnant is soaked at least partially into it. As suggested in Fig. 4 the impregnant fills about 45 half the thickness of the sheet 20 but in no case does it penetrate to the nap 22. Since the upper surface of the sheet 20 remains dry the nap having natural resilience remains lofted.

The composite sheet after leaving the squeeze 50 roll 18 may be festooned in a circuitous path and dried. Box toe blanks are then cut or die cut out of the composite sheet in substantially the shape 55 shown in Fig. 3 and these may be skived in the

usual manner. It will be understood that each blank contains a substantial film of thermoplastic or solvent softening composition and presents a napped surface well adapted to take up rapidly and retain a copious coating of cement when preparing it to be inserted in the shoe upper or preparatory to the pulling over or lasting operations.

In practice I have found it desirable to employ either double or single napped flannel or buckram as the textile material for the sheets 15 and 20. Satisfactory stiffening compositions may comprise polyvinyl resin in the form of a low viscosity emulsion or natural gums, resins and waxes such as montan, candelilla, carnauba or synthetic waxes such as "Mekan," "Sunwax," "Estawax," etc., or combinations of the same. Satisfactory thermoplastic compositions are cellulose acetate or nitrate ethyl cellulose, methacrylate, vinyl acetate, butyral, or chloride or combinations of the same.

The box toe material of my invention has been described heretofore as comprising two plies only but it is contemplated that three or more plies may be employed if desired. For example, one or more intermediate sheets of double napped fabric may be interposed between the sheets 15 and 20 shown in Fig. 1 with the result that the composite sheet immersing from the squeeze rollers 18 and 19 will have three distinct enclosed continuous films of the stiffening composition and an outer surface of lofted nap.

Having thus disclosed my invention, I claim as new and desire to secure by Letters Patent:

Box toe stiffening material in laminated sheet form comprising two woven textile sheets united in continuous face-to-face engagement, one of said sheets being completely saturated with a thermoplastic stiffening compound and the other sheet being saturated with the same compound only part way through from its inner surface and having an outer surface of lofted nap which is dry and retains its natural resilience and will rapidly take up and retain cement applied thereto, and an intermediate film of the same stiffening compound enclosed between the two sheets, the laminated sheet being moldable when heated and stiff and resilient at normal temperature.
